UNITED STATES PATENT OFFICE.

JOHN F. O'ROURKE, OF NEW YORK, N. Y.

FLYING-MACHINE.

1,144,052.

Specification of Letters Patent. Patented June 22, 1915.

Application filed December 4, 1909. Serial No. 531,414.

To all whom it may concern:

Be it known that I, JOHN F. O'ROURKE, a citizen of the United States, and a resident of the city, county, and State of New York, have invented certain new and useful Improvements in Flying-Machines, of which the following is a specification.

My invention relates to improvements in that class of so-called flying machines commonly designated aeroplanes; usually comprising a suitable frame provided with one or more suitably arranged planes serving to maintain the machine in the air during flight.

15 The principal object of my invention is to provide means tending to cause the machine to maintain a proper position in the air during flight or travel, such means operating automatically or under the control 20 of the operator as occasion may require. By having such means operate automatically, as hereinafter explained, a considerable amount of observation, skill and physical exertions on the part of the operator, as 25 heretofore required in operating aeroplanes, is reduced, leaving the operator free to perform or aid in performing any of the required manipulations or operations incident to controlling the aeroplane during flight.

30 Other objects of my invention comprise the provision of means whereby the machine may be steered in the desired direction, and the retardation of its forward movement and alighting facilitated, and 35 also, generally, to improve the general operation of the aeroplane, all to the end that the desired equilibrium of the aeroplane may be restored and efficiently maintained without overtaxing the aviator while contributing to the security of the aeroplane 40 and its occupant.

In carrying out my invention I provide a suitably constructed aeroplane, which may be either of the monoplane, bi-plane or 45 other type, and equip the same with suitably arranged supplementary or auxiliary planes movable independently of the main or supporting plane or planes, and I connect said auxiliary planes with means acting 50 by the force of gravity to impart to said auxiliary planes such movement as will tend or serve to cause the restoration of the aeroplane to its normal position of equilibrium in the air when such position has 55 been disturbed, which means comprises a weighted member suitably connected with

the auxiliary planes and connected with the main plane in such a universal manner that said member, tending normally to hang in a vertical direction, will, when the aeroplane tilts to the right or left, or fore or aft, cause such movement of the appropriate auxiliary plane or planes as will present them at such angle to the horizontal or to the main plane as will tend to cause the 60 normal level or equilibrium of the aeroplane to be restored. My improvements comprise means whereby the relative angular relation of said supplementary or auxiliary planes may be adjusted with respect 65 to the aeroplane as a whole, and continue as adjusted so that the opposite equal movements that may be imparted to said planes by the operating member or by the operator will cause angles of incidence tending to 70 attain the desired rotation laterally and to maintain the desired direction of flight longitudinally by properly meeting the aerial forces, and further to provide means whereby said supplementary or auxiliary 75 planes may be adjusted with respect to each other so that their normal relation to the operating member will be altered to cause them to act in accordance with such adjustment as respects their movement by 80 said operating member.

I will now describe preferred means whereby the aforesaid and other objects of my invention may be attained, it being understood that the same is not confined to 90 such specifically.

In the accompanying drawings: Figure 1 is a plan or top view of a flying machine embodying one form of application of my said invention, certain details shown in 95 some of the hereinafter referred to figures being omitted; Fig. 2 is an enlarged cross section on line $x-x$ of Fig. 1; Fig. 3 is an enlarged plan of one of my lateral auxiliary planes and its connections; Fig. 4 is an enlarged cross section of Fig. 3 on line $y-y$; Fig. 5 is an enlarged detail view illustrating the working end of the lever that operates the aforesaid auxiliary planes and its 100 relation to members comprised in its connection with said planes. Fig. 6 is an enlarged top plan of Fig. 5; Fig. 7 is, partly in section, an enlarged detail view of devices for securing fabric to the planes; Fig. 8 is an enlarged elevation, parts being 105 shown in vertical section on line $z-z$ of Fig. 2, seen in the direction of the arrow,

some transverse members being broken; Fig. 9 is a fragmentary detail end view showing pivotal mounting of rear plane; Fig. 10 is a diagrammatic view of an alternative construction of parts shown in Fig. 8; Fig. 11 is an enlarged detail inverted plan view of means providing for adjustability between the weighted member and parts connected therewith for controlling movable planes.

The flying machine or aeroplane illustrated comprises a main plane B of any preferred construction, having a suitable frame from which the frame A projects rearwardly substantially in the direction of flight. The frame of plane B illustrated comprises a front member or supporting rod 1, rear member or supporting rod 2, connected by cross braces 3 and 5, and further braced by diagonally disposed ties indicated by the dotted lines in Fig. 1, the frame thereby constituted being covered or inclosed by impervious fabric 4 in the usually approved manner of constructing aeroplanes. Such fabric is preferably secured to said frame as at fittings 82 on rods 1, by bolts 83, washers 85 and nuts 84, the fabric being clamped between 85 and 82 as shown in Fig. 7, and the remaining edges of the fabric laced or otherwise secured to their proximate frame members. Said frame members are firmly secured or clamped in any convenient manner to the skeleton frame A, as for instance, to longitudinal rods a a' of the latter that project from the main frame of plane B in the direction of flight. I have shown the rods a a' united by upright cross braces b and transverse cross braces c c strengthened by diagonal ties d d in any usual disposition and manner of connection, as indicated, for instance, in Figs. 1 and 2. It will be observed that the upper longitudinally extending rods a c are disposed angularly to the lower rods a a' . The rods or members 1, 2, at their extremities are shown connected by cross braces 6 to constitute extension frames for the auxiliary planes 7, 8, that are located adjacent the ends of the main plane B. I have shown plane B as pitched upwardly in a forward direction with respect to the normal position or equilibrium of the machine, and the normal disposition of the auxiliary planes 7 and 8 is preferably angular to that of plane B, as shown in Figs. 2 and 4, it being of advantage that the auxiliary lateral planes 7, 8, be normally in parallelism with the direction of flight or with the horizontal. According to this arrangement the normal initial angle between the auxiliary planes 7, 8, and plane B is preferably the same as that of the latter to the horizontal when the machine is at rest when plane B is pitched upwardly as described. If, however, plane B normally

is arranged in a horizontal manner, then the initial position of planes 7 and 8 could be parallel to plane B, although by the means hereinafter described for adjusting planes 7 and 8 their normal or initial angle respecting plane B may be any angle desired. In either case it is preferable that when the machine is flying horizontally the said supplementary planes should be substantially horizontal also. By "initial" angle I mean such angle as the supplementary or auxiliary planes may have relatively to plane B or to each other before they are changed or adjusted to any new angle or position.

I have shown the terminal or lateral supplementary planes 7 and 8 supported and arranged for operation in such manner that said planes, either automatically or at the will of the aviator, will be tilted in opposite directions as conditions may require, and I provide means for adjustment of said planes so that they may be set equally in the same direction at any desired angle with respect to the horizontal, and thus with respect to plane B, and I provide means to permit said supplementary planes to be adjusted in opposite directions, all with respect to the operating member of said planes, whereby said planes will be tilted simultaneously by their operating member while maintaining any of such relative angular relations to each other. Said supplementary planes are thus adapted to operate or be operated to maintain or tend to maintain the machine in the position best suited to the existing conditions of flight. To these ends I have provided arrangements as follows:

Referring to Fig. 3, 12 are blocks or bearings, in this instance constituting unions for elements of cross braces 5, 6, and of sufficient dimension to provide therein journals for shaft 13 passing through blocks or unions 14 comprised in frame 9 of the corresponding supplementary planes 7 and 8. Shaft 13 is rigidly secured to blocks 14 by pins 15 whereby the planes 7 and 8 are supported and adapted to rotate with the corresponding shaft 13, and whereby their angular disposition relatively to the main plane, or to each other, or their angles of incidence to the air, may be varied by the appropriate rotation or adjustment of shafts 13. To produce such variations I provide means as follows: Brackets 23 rigidly supported by rods 24 secured to cross braces 3' and 5' of the main frame of plane B carry bell crank levers 17 and 18 pivotally connected with brackets 23 and connected with shafts 13 by arms 16 and adjustable links 19 shown comprising members 20 and 21 connected for adjustment by turn buckles 22, the members 21 being preferably of a universal joint construction, as shown. The corresponding ends of bell crank levers 17 and 18 are shown

pivotally connected by links 27 with longitudinally movable rods 25, Fig. 1, slidably supported in bearings 26 shown carried by cross braces 3 of the frame of plane B (Fig. 8). The inner ends of rods 25 are shown pivotally connected by means of links 28 (Figs. 1 and 5) with disk 29 supported normally fixedly by lever 30, but which disk is connected with lever 30 in such manner as to permit desired adjustment of said disk for the purpose of adjusting planes 7 and 8 in the same direction simultaneously and preferably to an equal extent. Lever 30 is shown pivotally supported by pivot 30^a carried by frame or spider 31, Figs. 2 and 8, rigidly secured to and supported by the main frame, being shown supported by upright cross braces b³² of frame A (Figs. 1 and 2). The arrangement of arms 16, bell crank levers 17, 18, lever 30 and the connections between said parts as illustrated provide means whereby when lever 30 is in a normal or vertical position, the planes 7 and 8 will be in any desired set position with respect to each other, and to plane B, and that when the end of lever 30, above its pivotal point 30^a, is moved to the right or left, or its normal rectangular position with respect to plane B is altered, planes 7 and 8 will be moved or tilted simultaneously in opposite directions, so that the forward edge of one of the auxiliary planes will thereby be tilted downwardly while the corresponding edge of the other auxiliary plane will be tilted upwardly to an extent corresponding to the aforesaid movement or shifting of position of lever 30 relatively to plane B, and such movements of planes 7 and 8 will, according to the arrangements described, be equal in extent, thus presenting to the air the planes 7 and 8 at angles corresponding to the movements imparted to said planes by lever 30. While planes 7 and 8 may be parallel with each other at such time as lever 30 is in the vertical position and plane B is horizontal, to thus have said planes at such time in any desired position with respect to the horizontal, as for instance, in a horizontal position, I provide means whereby such normal initial like angles of said supplementary planes to plane B may be, at the will of the aviator, within limits, modified equally and said planes be adjusted or set to new initial angles without interfering with the capacity of the supplementary planes to have movement simultaneously in opposite directions. The means I have shown for this purpose are as follows: Disk 29 is, as aforesaid, carried normally fixedly by lever 30, but adapted to be rotated thereon to simultaneously move rods 25 toward or from each other, whereby planes 7 and 8 will be adjusted equally simultaneously in the same direction. To this end the upper end of lever 30 is provided with a bearing 66 within which is rotatably held a spindle 67 carried by disk 29. Serrations or teeth as at 68 are shown provided upon the periphery of bearing 66. A pair of oppositely disposed bell crank levers or pawls 64, 65 are rotatably carried by disk 29 by pivotal connections 64', 65'. Each of said pawls has its major arm provided with a tongue 69, oppositely disposed relatively to each other and adapted to engage the serrations or teeth 68. One of said pawls carries on its minor arm a pin 65^a (Fig. 6), the minor arm of the other of said pawls being provided with a slot 64^a containing, and within which pin 65^a plays. Tongues 69 of said pawls are normally held in engagement with serrations or teeth 68 of bearings 66 by stress of the springs 70 connecting said pawls with disk 29. From the outer end of the major arm of each of said pawls extends a cord or connection 71, 72 respectively, which are shown passing over idlers 73, 74 and 75 and 76, (Fig. 8), to terminate at points conveniently adjacent to the aviator's position. The idlers 74 and 76 are rotatively mounted on cross rods 77 carried by upright cross braces b³² of frame A, Figs. 2 and 8, and the idlers 73 and 75 are similarly carried by cross rods 78 supported by the longitudinal corresponding rods a a of said frame. The construction described is such that a downward pull by the aviator on either of the cords 71 or 72 will lift one of the tongues 69 of the corresponding pawl out of engagement with a serration 68 in bearing 66, thereby simultaneously releasing also, owing to the pin and slot connection noted, the opposite tongue 69 from its similar engagement with a serration 68, and thus unlocking disk 29 from lever 30 to the extent of permitting said disk to rotate relatively to said lever. 105

80, 81 are stop pins carried by disk 29 to limit movement imparted to the pawl by the aforesaid pull. It follows that a continuation of said pull by the aviator after unlocking disk 29 from lever 30 will result in 110 rotating said disk relatively to lever 30 in directions determined by whichever of the two cords 71 or 72 is pulled. It thus follows that both rods 25 may be simultaneously pulled inward toward each other or pushed apart by the aviator within limits as desired, whereby through the medium of the bell crank levers 17, 18, arms 16, and connections of said parts with the auxiliary planes and with disk 29, said planes will be 115 simultaneously equally adjusted with respect to their previous angle respecting the plane B, and this can be accomplished without interfering with the operation of planes 7 and 8 by lever 30 in opposite directions. 120 Therefore, the aviator may, at will, by pulling on said cords as occasion requires, turn to the extent desired both of said auxiliary planes 7 and 8 in the same direction or to greater or less angles thereof with respect 125

130

to plane B as compared with their preceding angles relatively to said plane. It will be observed that when the aviator releases the cord the disk 29 will be again locked in such 5 adjusted position with respect to lever 30 leaving planes 7 and 8 set in such position of adjustment until such time as a new adjustment of said planes is desired, said planes thus remaining set at such relative 10 angle as long as desired. Planes 7 and 8 may be restored to their initial angular relation to main plane B or moved to any other desired angle relatively thereto as and when desired at the will of the aviator by operating 15 of the cords 70 or 71.

Means for operating lever 30 to cause adjustment of auxiliary planes 7 and 8 with respect to plane B may be effected automatically or by the action of the operator, 20 whereby when the aeroplane tilts from the position of equilibrium or stability during flight it will be quickly restored to its previous position or to such other position in the air as may be desired. The means I have 25 shown for this purpose are as follows: The lower portion of lever 30 is connected with a weighted or gravitated member 51 suspended from the main frame of the machine, and to this end I have shown the lower end of 30 lever 30 as terminating in fork 33 straddling the horizontally disposed lever 34 pivoted as at 35 to one of the transverse cross braces c^{30} of frame A. The opposite or forward 35 end of lever 34 passes freely through yoke 37 or head 37 of swivel 38 (Fig. 8), adjustably secured to weighted member or carrier 51. In the arrangement shown member or carrier 51 is provided with a seat 52 for the 40 aviator. Member or carrier 51 is loosely suspended from the main frame of the machine, and in a universal manner, so as to be free to swing in any direction, the arrangement for which purpose I have shown comprising four hangers 53, one for each of the 45 corners of member 51. Hangers 53 have at their lower ends eyes 54 loosely engaging the eye bolts 55 on member 51, and at their upper end eyes 56 loosely engage with eye bolts 57 shown carried by brackets 58 sup- 50 ported at cross rods 59 carried by the rods a of the main frame (Figs. 1 and 8). The pivotal means described of connecting member or carrier 51 with the frame of the machine and the connection of said member 55 with the auxiliary planes by the mechanism described permits movement of said member in substantially all directions, and causes lever 34 to partake of some of the movements of said member, whereby said weighted member is, by gravity, caused to maintain a substantially vertical position relative to the flying machine as a whole, notwithstanding movements of such machine in various 60 directions.

65 When the aeroplane is in a normal or

horizontal position of equilibrium and weighted member 51 hangs in a normal position with respect to the machine, lever 30 will hang in a corresponding vertical position and the planes 7 and 8 will be in their 70 normal position or at the initial angle with respect to the horizontal, which may be any desired angle with respect to plane B, such as before described. If now the aeroplane tilts to the right or left of the longitudinal 75 center or direction of flight, the weighted member 51 and lever 30 will maintain a substantially vertical position, and the result will be that by reason of the described connection of the upper end of lever 30 with 80 planes 7 and 8 movement will be imparted to the auxiliary planes 7 and 8 through the medium of levers 30 and 34, and the connections from lever 30 to said planes, causing said auxiliary planes to swing upon 85 their axes 13 relatively to plane B in proportion to the extent of tilting or dipping of the aeroplanes, whereby the angle of incidence to the air of said auxiliary planes is increased or decreased, respectively, and the 90 tendency of the aeroplane to dip downwardly on the low side is resisted, as more fully hereinafter explained.

The above described movements of planes 95 7 and 8 are assumed to be automatic by reason of the connection of said planes with the weighted member or carrier 51. In order to enable the operator at will to cause adjustment of auxiliary planes 7 and 8, to 100 vary their angles of incidence to the air or to the plane of the direction of flight, he may, while sitting in the seat 52, take hold of any suitable part of the main frame or he may grasp a rail 61 shown carried by upright cross braces b^{32} of the main frame of 105 the machine, which rail is shown encircling hangers 53. Thereby the aviator, suspended in the weight carrying member 51, may, by his own action, cause member 51 to swing 110 in a desired direction to carry said member 51 out of its normal position maintained by gravity, whereby force is transmitted to the auxiliary planes to at will vary the angles of incidence of said planes, to the air as desired. 115

I provide means additional to the planes 7 and 8 to assist automatic regulation or maintenance, or control at the will of the operator, of the angular or fore and aft relation of the aeroplane to the direction of flight, such as to cause the machine to dip downwardly in a forward direction or incline upwardly in such direction, or to resist or rectify the tendency of the machine to such movements. To this end I have shown an auxiliary plane 46 constructed similarly to the auxiliary planes 7 and 8 and disposed more central than said auxiliary planes, as in a line between said planes. I have shown 120 plane 46 as located at the rear of the ma- 125

chine, although such position of said plane may be altered, as for instance, such plane may be at the forward end of the machine, or one such plane may be at the forward end, and another such plane at the rear end. Plane 46 is shown provided with a shaft 44 journaled loosely in the blocks or unions 48, Fig. 9, connecting elements of upright cross braces 10 ^b by which the longitudinally extending rods *a*, *a'* of frame A are united at their rearward ends. Arm 43 carried by shaft 44 is at its lower end pivotally connected with one end of rod 42, the other end of which 15 carries eye 41 (Fig. 8) through which passes loosely pin 39 having collar 40, said pin being carried by yoke 37. It will be understood that I have in the drawings illustrated said rod 42 diagrammatically and suggestively and that the same comprises, as suggested by the vertically disposed portion thereof shown in Fig. 2, a rocker member pivotally connected and medially rotatively supported, whereby direction of motion 20 imparted by pin 39 is reversed when communicated to arm 43. From this construction it follows that if the machine and its aeroplane tilt in the direction of flight unduly upwardly or downwardly, forward or 25 rearward of its central longitudinal axis, gravity acting upon the weighted member 51 will transmit through rod 42 force to arm 43 to rotate shaft 44 and thus modify the angle of incidence to the air of plane 46 to 30 resist such undesired dipping and to aid in restoring the aeroplane to its proper position, and will do this automatically, and without action on the part of the aviator. It will also be understood that the aviator 35 40 may cause the operation of plane 46 at will by causing movement of weighted member 51 forwardly or rearwardly, such as, when seated in said member, the aviator may pull the member forwardly or push it rearwardly for the purpose. For instance, if 45 the aviator desires to cause the aeroplane to rise or descend he may voluntarily cause weighted member 51 to swing in the proper direction to transmit desired motion to plane 46, or by such motion given by him to weighted member 51 the aviator may quickly correct any tendency of the aeroplane to deviate in an upward or downward direction from the course the aviator desires, 50 by causing proper movement of plane 46 through such desired movement of member 51. In addition to rail 61 being in convenient position to enable the aviator to at will, while sitting in weighted member 51, 55 operate said member for the purpose stated, the rail 61, by encircling hangers 53, will restrain oscillation of member 51, or vice versa, to oppose to an extent oscillation of the aeroplane relatively to said weighted member. 60

In order that adjustment between weighted member 51 and the parts connecting the same with planes 7 and 8 and 46 may be made, I have shown means whereby the relation of swivel 38 to its normal position respecting member 51 may be varied at will, and said swivel left in adjusted position, whereby the normal relative angles of planes 7 and 8 or of plane 46, or both, to each other or to member 51 may be regulated as circumstances may require. To this end I have shown the following means: A 70 sliding plate 87 is attached to the bottom of member 51 by screw bolts 92 passing loosely through longitudinal slots 91 in said 75 plate (Fig. 11), said plate also having a transverse slot 90. Swivel 38 is shown provided with a threaded bolt 88 which passes through transverse slot 90 of plate 87 and is held in place thereon by nut 89. By adjusting swivel 38 in either direction through slot 90 of plate 87 and fastening swivel 38 in such position, it will be understood that lateral movement is thereby imparted to lever 34 which will cause tilting of lever 30 80 relatively to its normal position respecting weighted member 51, and thereby, as the upper end of lever 30 is swung to a corresponding extent to the right or left, the rods 25 and the connections therefrom to 85 planes 7 and 8 will cause said planes to be tilted in opposite directions more or less respecting their previous angles with relation to plane B, causing thereby a change in the normal or previous angles of incidence of 90 said planes to the air, while weighted member 51 hangs vertically, and such new angles of planes 7 and 8 will remain constant with respect to the normal position of said member 51, while swivel 38 remains in such ad- 95 justed position during movements imparted to planes 7 and 8 by member 51. Hence, if the aviator finds it desirable at any time to alter the normal or initial angles of the planes 7 and 8 to plane B he may shift 100 swivel 38 to the right or left and lock or set the same in a new position respecting member 51, and when the aviator desires to restore said planes to their previous initial or other angle respecting plane B, he will 105 110 again shift swivel 38 and set or lock the same.

The movements of planes 7 and 8 in opposite directions by lever 30, automatically or at the will of the aviator, will occur as before described with said planes set or adjusted relatively to each other as last described. A corresponding fore and aft adjustment of swivel 38 may be made by the aviator when desired to cause a change of 115 normal relation or angle of plane 46 with respect to the normal position of weighted member 51. For this purpose I have provided a link 95 secured to and projecting from plate 37, to which link is pivotally con- 120 125 130

nected lever 96 projecting upwardly to within convenient reaching distance of the operator. Lever 96 is fulcrumed to stud 97 attached to said member 51 and may be provided with a locking segment of usual construction 98 and adjuncts usually employed to lock such lever in the desired position. By this means as swivel 38 is connected with plate 87 the latter may be adjusted fore or aft respecting the weighted member 51, thereby causing a corresponding tilting of plane 46, and by setting plane 46 at such new angle respecting member 51 the movements of the latter relatively to plane B will be communicated to plane 46 in the manner before described, but the effect will be modified in accordance with such annular position of plane 46. The utility of this arrangement will be obvious when it is considered that if the aviator ordinarily sits in seat 52 proper balance of the aeroplane, so far as the weight of the aviator is concerned, will be maintained, but should the aviator desire to move from the seat, as forwardly to adjust the engine that may be located in front of the seat, his weight thus advanced toward the front of the aeroplane would have a tendency to cause the latter to dip downwardly at the front, but by means of lever 96 and the parts connected therewith for adjusting plane 46, as the aviator moves forwardly he may adjust lever 96 to a suitable extent to cause angular adjustment of plane 46 to present the latter at such angle to the air as will tend or serve to counteract the weight of the aviator as he moves away from or back toward seat 52. Thus, the aviator will feel free to move from seat 52 knowing that he may make an adjustment to accord in balancing the aeroplane with his shifted weight or position.

It will be understood that, if desired, the automatic action of my invention may be secured without utilizing the weight of the aviator to that end. In other words, the weighted member 51, tensioned by gravity, may be loaded by any other weight, including that of other articles or appliances desirable to be carried by the machine; also the construction and disposition of member 51 is not confined to that illustrated by the carrier or box. In Fig. 10 I have illustrated fragmentarily and diagrammatically an alternative construction in which the weighted member 94 consisting of, or containing, any sufficiently heavy article or substance, is secured directly to lever 30, the automatic operation being, as regards the laterally disposed auxiliary planes 7 and 8, substantially the same as before described.

I have shown flexible checks 94' (Fig. 4) connected with the main frame and with the planes 7 and 8, which checks may be of cord or chain. Said checks serve to limit undue

swinging movements of planes 7 and 8 in opposite directions and aid in relieving strain on the parts when said planes are at angles to the main plane that would cause the greatest strain upon planes 7 and 8.

As shown in Fig. 2 rods a^2 are extended forwardly and upwardly at the front of the machine to fend the latter when alighting. Supporting wheels a^3 are likewise provided as usual to aid in supporting the machine and to receive impact when the machine is grounded. To oppose sliding of the machine laterally when in flight I prefer to cover parts of the machine frame with vertically disposed fabric C.

The machine may be propelled in any well known manner, as by an engine and propeller or propellers arranged in any suitable relation, such as by having the engine supported in the main frame in front of the aviator. The relative arrangement of the parts will be such that when the aeroplane is in equilibrium and the weighted member 51 and lever 30 hang by gravity in a vertical position the adjustment or relative positions of auxiliary planes 7, 8 and 46 in connection with member 51 will be such as to cause the machine to rise from the ground as it is propelled forwardly. With the planes 7, 8 and 46 normally maintained in horizontal relation and the main plane B inclined forwardly and upwardly the tendency of the aeroplane will be to rise, and the aviator may regulate such rising by operating lever 96 to alter the angle of incidence of plane 46 to the air as desired, or the aviator may at will move the seat 51 forwardly to cause plane 46 to incline downwardly and forwardly to direct the aeroplane upwardly, and the aviator may reverse the position of plane 46 to cause forward and downward flight of the aeroplane. If, however, the aeroplane during flight tends to rise or dip downwardly, such action will be automatically controlled or rectified by reason of the new angle assumed by weighted member 51 relatively to the aeroplane causing proper adjustment of plane 46. If the aeroplane tends to dip to the right or left the new angle or angles assumed by weighted member 51 relative to the main frame will cause lateral movement of lever 30, which by pushing and pulling on rods 25 will cause planes 7 and 8 simultaneously and equally to assume new angles relatively to plane B, the forward edge of one of the lateral planes extending downwardly and the corresponding edge of the other lateral plane rising to present said planes at equal but opposite angles to the air, thereby tending to cause the low side of plane B to rise and the high side of plane B to descend, thereby tending or serving to automatically rectify the lateral tilting of the aeroplane.

and such angular movement of planes 7 and 8 will accord with the extent of lateral tilting of the aeroplanes as a whole.

If the aviator finds that it is desirable, at any period, to increase or diminish the then angles of planes 7 and 8 to the air, he may accomplish this by pulling, to the extent desired, one of the cords 71 or 72, thereby setting planes 7 and 8 simultaneously in the same direction to new angles respecting plane B, but such planes will retain their previous angle respecting each other and in such new angular relation said planes will continue to operate as before described under the influence of weighted member 51. By next pulling upon the proper cord 71 or 72 the aviator may restore planes 7 and 8 to their previous angular relation or change them to such other angle as he may desire. In addition to the automatic action of planes 7 and 8 as controlled or influenced by weighted member 51, the aviator may, as desired, by causing movement of member 51, as by grasping rail 61, and pushing or pulling in the desired direction, cause the planes 7 and 8 to assume angles of incidence to the air different from the angles said planes then would assume under the automatic action of weighted member 51 and then by releasing rail 61 member 51 will assume its normal hanging position and planes 7 and 8 will assume angles relatively to plane B that correspond to the angular position of said plane respecting member 51. Likewise, by shifting weighted member 51 fore or aft plane 46 may be controlled, and by shifting member 51 to an angular position within either space bounded by lines passing through the longitudinal and transverse axes of the aeroplanes respecting the normal center of member 51, the auxiliary planes 7 and 8 and 46 may be simultaneously adjusted at the will of the aviator to new angles that will accord with the extent of such angular movement the aviator gives to member 51. The aviator may, at any time, adjust planes 7 and 8 for different angles relatively to plane B by adjusting swivel 38 through slot 90, whereby the forward edge of one lateral plane will be moved downwardly and the corresponding edge of the other lateral plane will be moved upwardly and said planes be set in such new angular relation to each other, and the automatic control of said planes, or control thereof at the will of the operator with said planes in such position, will occur until said swivel is again readjusted to its normal or other position, and so on. Adjustment may also be made of plane 46 by operating lever 96 to set plane 46 in a new angular relation to the air for control by member 51 while planes 7 and 8 are set in a position other than normal or otherwise, and with the planes set in such new adjusted

positions the automatic operation, or operation under the control of the aviator, will occur in accordance with such angles of such planes. If the aviator desires to turn the machine laterally toward the right he grasps rail 61 on his left and by pulling in that direction and somewhat forwardly, with the amount of force required, modifies the angles of incidence to the air of the aeroplane to cause the left side of the aeroplane to lift and the right side to descend, and at the same time tilts the machine upward in the direction of flight, thus imparting to the machine a turning movement toward the right the degree of force exerted by the aviator and consequent voluntary modification of normal relation between the weighted member and the remainder of the machine being graduated from the turning movement to meet the requirements of the case, and describe the desired curve in direction. After this is completed the operator releases his hold on rail 61, leaving the weighted member to perform, as before, its automatic equalizing function during straight flight. The aeroplane would be turned to the left by the aviator grasping rail 61 to the right and swinging member 51 in such direction, causing the auxiliary planes to operate correspondingly in manner before described. If it is desired to cause a relatively long flight in an upwardly inclined direction, the aviator may, by adjusting lever 96 to the desired extent, cause auxiliary plane 46 to be set respecting member 51 at the desired angle, and then the automatic actions during such inclined flight may take place as required, and then if the aviator desires to descend or coast in a downward and forward direction he may again adjust lever 96 relatively to member 51 to set auxiliary plane 46 in the desired position for such flight and the automatic actions described will continue to occur. During either of such flights the aviator may change the angle of plane 46 to the air, without changing its normal set relation to member 51 by imparting to such member 51 the desired movement in a forward or rearward direction relative to the machine as a whole, and then by releasing member 51 the parts will resume automatic action according with their positions relatively to each other. For some purpose, as for quick rising, as when starting flight, the aviator may, by pulling on one of the cords 71 or 72, set planes 7 and 8 equally and simultaneously at any desired angle of incidence to the air different from their normal positions when the aeroplane is in equilibrium, such as by causing both planes 7 and 8 to be projected somewhat upwardly at their forward edges, and then automatic action of said planes, or their action at the will of the aviator, will occur with the

- planes 7 and 8 in such relative positions until the aviator again operates the appropriate cord 71 or 72 to restore said planes to their normal or other positions, and the aviator may likewise set plane 46, by adjusting lever 96, at such angle as will aid or modify such action of planes 7 and 8, and while leaving planes 7 and 8 set in such described positions relative to each other, he may alter the position of plane 46 relative to member 51, or he may leave plane 46 in such described set position and alter the position of planes 7 and 8 relative to member 51 or to each other, according to circumstances.
- Again, when the aviator desires to descend he may set the auxiliary planes 7 and 8 to the required angle of incidence to the air, as in parallelism with each other, and without substantial interference with the previously described regulation thereof.
- From what has been described it will be understood that the auxiliary planes when set in normal position connected with weighted member 51 will act automatically with a tendency to prevent deviation of the aeroplane from a normal position of equilibrium, and to an extent substantially commensurate with such deviation; also that said planes may be adjusted relatively to each other to continue such automatic actions in such adjusted positions; that the lateral planes may also be simultaneously adjusted in the same direction and to an equal extent and will then partake of automatic movements while in such new relative positions, maintaining such positions while one lateral plane is presented at a greater angle to the air than the other, as the case may be; that plane 46 may be adjusted as required to accord with adjustment of planes 7 and 8 or irrespective thereof, and further that with the planes set in any desired positions relatively to plane B or to each other, or both, the ensuing automatic action of said planes may be supplemented temporarily, or to the extent desired, by the will of the operator, all whereby control of the machine in rising, in soaring upwardly or descending, and in alighting is greatly facilitated, which movements may be accomplished gradually and smoothly or abruptly, and at the same time safely.
- It will be understood that the positions of pivotal support 30^a and disk 29 and its connections relatively to lever 30 may be inverted, *i. e.* said lever rotatably suspended above the skeleton frame and disk 29 and its connections located on said lever below the point of its said suspension with equivalent results, except that in such case, as is obvious, the directions of movement of said connections with said disk will be reversed, without otherwise modifying their functions or effects; also that the operation and effects

of my said inventions are not confined to a monoplane, as shown in the drawings, but are equally applicable to bi-planes or to aeroplanes having any desired number of main planes superimposed or otherwise; also that as rudder or otherwise, an additional auxiliary plane or planes, rotatable on shafts angularly disposed relatively to shafts 13 and 14, may be added and operated either independently of, or in connection with, the plane actuating devices described; also that the machine may be provided with means to generate power, additional to that of the operator, and propelling devices actuated by said means, and that latter may be controlled and directed by the operator from weighted member 51 electrically, through flexible connections or otherwise, or that said member, being sufficiently weighted otherwise than by the operator's body, the latter may leave same, as and when required, to reach other parts of the machine for purposes of manipulation, repair, etc., and that when the aviator moves about the machine, as hereinbefore stated, he may set or control plane 46 to aid in maintaining proper balance of the aeroplane.

What I claim as new and desire to secure by Letters Patent is the following, viz:—

1. A flying machine having one or more main planes and provided with movable planes, an operating member movably carried by said machine, connections interposed between said member and said movable planes to move them simultaneously in opposite directions, means comprised in said connections to move the parts of said connections in opposite directions to set said movable planes simultaneously in the same direction, and adjustable devices connecting said operating member with said connections for setting said planes in opposite directions relatively to each other to be operated by said member when set in the same or opposite directions.

2. A flying machine having one or more main planes and provided with movable planes, an operating member movably carried by said machine, connections between said movable planes and said member to move said planes in opposite directions by the action of said member, said connections comprising an adjustable member to move parts of said connections relatively to each other, means to lock said adjustable member and connections in operative relation to the first named member, and means to unlock said members to permit relative movement of said connections to set said planes in the same direction to be actuated by the operating member when so set.

3. A flying machine provided with movable planes, an operating member movably carried by said machine, connections between said planes to operate them simultane-

- ously, a lever operatively connected with said member and with said connections to move them in the same direction, means to change the relative positions of said connections to vary the angles of said planes relatively to each other, and means to adjust the position of said lever relatively to said member to set said planes in opposite directions relatively to each other.
- 10 4. A flying machine having one or more main planes and provided with movable planes carried adjacent to the ends of the main planes, an operating member movably carried by said machine, connections between said movable planes, a horizontally disposed lever movably connected with said member, a lever interposed between said connections and the first named lever, and means interposed between said member and said movable planes to adjust said planes in the same direction with respect to their previous angle relative to the machine, whereby said member will operate said movable planes during changes of position of said member relatively to the machine.
- 15 5. A flying machine having one or more main planes and provided with movable planes carried adjacent to the ends of the main planes, an operating member movably carried by said machine, connections between said movable planes, a horizontally disposed lever movably connected with said member, a lever interposed between said connections and the first named lever, and means 20 for adjusting the second named lever with relation to said member, whereby said member will operate said movable planes during changes of position of said member relatively to the machine.
- 20 6. A flying machine provided with movable planes, an operating member movably carried by said machine, connections between said planes, a lever pivotally carried by said machine and operatively connected with said member, a rotative head pivotally connected with said lever and comprised in said connections, means to lock said head in adjusted position respecting said lever, and means to at will unlock and adjust said head.
- 25 7. A flying machine provided with movable planes, an operating member movably carried by said machine, connections between said planes, a lever pivotally carried by said machine and operatively connected with said member, a rotative head pivotally connected with said lever and comprised in said connections, a toothed member connected with said head, pawls carried by said head to engage said toothed member, means to 30 maintain said pawls normally engaging said toothed member, and means to at will operate either of said pawls to unlock said head and rotate the same in either direction desired to adjust said planes.
- 35 8. A flying machine having one or more main planes and provided with movable planes, an operating member movably suspended from said machine, connections between said movable planes, a horizontally disposed lever carried by said machine and movably connected with said member, and an upwardly disposed lever carried by said machine and operatively connected with said connections and with the first named lever.
- 40 9. A flying machine provided with movable planes, an operating member movably suspended from said machine, connections between said movable planes, a horizontally disposed lever carried by said machine and movably connected with said member, an upwardly disposed lever carried by said machine and operatively connected with said connections and with the first named lever, and means to adjust the position of the first named lever with respect to said member.
- 45 10. A flying machine provided with movable planes, an operating member movably suspended from said machine, connections between said movable planes, a horizontally disposed lever carried by said machine, means connecting said lever with said member to permit said member to move freely in the direction of the length of said lever, and an upwardly disposed lever carried by said machine and operatively connected with said connections and with the first named lever.
- 50 11. A flying machine provided with movable planes having operating arms similarly disposed, bell crank levers carried by said machine and connected with said arms, connections between said bell crank levers to operate them in opposite directions when said connections move in one direction, an operating member movably carried by said machine, means movably connecting said member with said connections, and means to adjust said connections with respect to said member to set said planes in opposite directions relatively to each other.
- 55 12. A flying machine having one or more main planes and provided with a substantially centrally disposed movable plane, an operating member movably carried by said machine, connections between said plane and said member to operate the former by the latter, means to adjust said member with respect to said connections to vary the initial angle of said plane relatively to said member, said machine having lateral planes, connections between said planes to move them simultaneously, means operatively connecting said member with said connections, and means to set said lateral planes in the same direction with respect to their previous initial angle relative to the machine to be actuated by the operating member when so set.
- 60 13. A flying machine having one or more main planes and provided with a substantially centrally disposed movable plane, an

operating member movably carried by said machine, connections between said plane and said member to operate the former by the latter, and means to adjust said member 5 with respect to said connections to vary the initial angle of said plane relatively to said member, said machine having lateral planes, connections between said planes to move them simultaneously, means operatively 10 connecting said member with said connections, and means to set said lateral planes in opposite directions relatively to each other to be actuated by the operating member when so set.

15 14. A flying machine having one or more main planes and provided with a substantially centrally disposed movable plane, an operating member movably carried by said machine, connections between said plane 20 and said member to operate the former by the latter, means to adjust said member with respect to said connections to vary the initial angle of said plane relatively to said member, said machine having lateral planes, 25 connections between said planes to move them simultaneously, means operatively connecting said member with said connections, means to set said lateral planes in the same direction with respect to their 30 previous initial angle relatively to the machine, and means to set said lateral planes in opposite directions relatively to each other to be operated by said member while set in the same or opposite directions.

15 15. A flying machine provided with lateral planes, and a plane located in a line between the lateral planes, a member movably carried by said machine, connections between the lateral planes, a horizontally disposed lever carried by the machine and movably 40 connected with said member, an upwardly disposed lever operatively connected with the horizontal lever and with the said connections, and means connecting said member with said second named plane. 45

16. A flying machine provided with lateral planes and a plane located in a line between the lateral planes, a member movably carried by said machine, connections between the lateral planes, a horizontally disposed lever carried by the machine and movably 50 connected with said member, an upwardly disposed lever operatively connected with the horizontal lever, and with said 55 connections, means connecting said member with said second named plane, and devices connecting said horizontal lever with said member and adjustable transversely of the machine to adjust the lateral planes in opposite directions relatively to each other, 60 said devices being adjustable longitudinally of the machine with respect to said member to adjust the second named plane relatively to said member.

JOHN F. O'OURKE.
